[57] CLAIM

The ornamental design for a jar, as shown and described.

DESCRIPTION

FIG. 1 is a perspective view of a jar;
FIG. 2 is a view of the front of the jar;
FIG. 3 is a view of the top of the jar;
FIG. 4 is a view of the bottom of the jar;
FIG. 5 is a view of the right side of the jar; and,
FIG. 6 is a view of the left side of the jar.
No view of the back of the jar is shown since it is the mirror image of the front.
